UNITED STATES PATENT OFFICE.

ALVIN WOODMAN, OF LEWISTON, MAINE, ASSIGNOR TO HIMSELF AND CYRUS I. BARKER, OF SAME PLACE.

CLOTH TENTERING, DRYING, AND CALENDERING MACHINE.

SPECIFICATION forming part of Letters Patent No. 253,806, dated February 14, 1882.
Application filed March 14, 1881. (No model.)

To all whom it may concern:

Be it known that I, ALVIN WOODMAN, of Lewiston, in the county of Androscoggin and State of Maine, have invented a new and useful Improvement in Cloth Tentering, Drying, and Calendering Machines, of which the following is a full, clear, and exact description.

My improvements relate to machines used for drying, tentering, and calendering woven fabrics of cotton, wool, flax, silk, or other material that requires to be dried and tentered.

The object of my improvements is to provide for tentering the cloth to any required width, and rendering the goods of uniform width, with checks or plaids running straight, as designed, instead of being crooked, bowed, or otherwise disfigured.

My invention consists in certain novel features of construction and combinations of parts for obtaining said object, as hereinafter described and claimed with reference to the drawings.

In the drawings, Figure 1 is a vertical longitudinal section of a tentering, drying, and calendering machine containing my improvements. Fig. 2 is a vertical transverse section of the same on line $x-x$ of Fig. 1. Fig. 3 is a partial plan view, showing the straightening-rolls. Fig. 4 is a face view of the straightening-rolls. Fig. 5 is a section on line $y-y$ of Fig. 3. Fig. 6 is a detail sectional view. Fig. 7 is a detail of a modification; and Fig. 8 is a plan view of the machine, with some of the parts omitted or broken away, showing principally the tentering mechanism and a modified form of driving-gear.

Similar letters of reference indicate corresponding parts.

The frame A of the machine is of usual character. At the feeding end is placed a roll, a, which carries the cloth.

b is the spreader. c is the size-box. d d are squeezing-rolls. e' e' are carrier-rolls by which the cloth is held to the surface of cylinders e, the latter revolved by the friction of the cloth. These parts are as usual, except the spreader b, which consists of two semicircular bars, b², of metal or other suitable material, attached to end pieces, b', that are pivoted in suitable

bearings, so that the bars are held parallel 50 and may turn with the end pieces, b'.

A ratchet-wheel, c², (shown in Figs. 1 and 8,) is fitted to one pivot of the spreader, and is engaged by a pawl, d², for retaining the spreader in position. This allows adjustment, 55 so that the cloth will bear upon more or less of the surface of the bars b², thereby varying the friction, as the case may require. The spreader-bars are fluted diagonally from the center outward.

From the cylinders to the straightening mechanism at the other end of the frame two endless chains, B, are provided for carrying the cloth. The chains consist of flat links jointed together, and are carried by chain-wheels g, that are hung at the sides of the machine. The links have spurs or points, as shown, for catching the edges of the cloth, and they are formed with slots for engagement with the teeth of chain-wheels g. There are 70 revolving brushes h fitted above the chains for pressing the cloth upon the pins. These are placed at the point where the cloth and chain come together in contact with the face of the links.

The chains B are supported on tracks or guide-strips k, that rest on brackets k', secured to the side rails of the machine, as shown clearly in Fig. 2. The guide-strips k are grooved to receive the chains, and are constructed in 80 two sections at each side, the first section at each side extending obliquely outward from the feed end, and the second sections extending parallel, so that the cloth is first widened gradually and then retained at the full width. 85

For adjustment of the guides and tracks I provide screw-shafts l, which are sustained by the siderails of the machine beneath and across the strips k and carry nuts l' l'', which are connected to the guide-tracks. The shafts have 90 right-and-left-handed screws, and are fitted with hand-wheels l² for their operation. There are three of these screw-shafts, one at the feed ends of the tracks, one at the delivery end, and a third at the inner ends or junction of the 95 two sections, fitted to move those ends of both sections at each side. The shaft at the feed end is for adjustment of the narrower end of

the track. The shaft at the delivery end carries a bevel-pinion, engaging with a similar pinion on a shaft, l^3 , that extends to and is geared with the middle shaft, l . This allows 5 simultaneous adjustment of both ends of the parallel tracks and the wider ends of the diagonal tracks at one operation.

In Fig. 1 I have shown the chain-wheels driven by pulleys g^2 and belts g^3 , roll w being also 10 driven by a belt, g^3 , from pulley g^2 ; but I shall also use the means shown in Fig. 8, and also partly shown in Fig. 7, where the chain-wheels are loosely mounted on long sleeve-nuts that are carried by the shaft l at the delivery end 15 of the machine. An arm, l^4 , attached to the nut l^4 , passes to the guide k , whereby the guide and wheel are adjusted simultaneously by turning the shaft. The chain-wheel g at the delivery end is formed with a gear-wheel, l^5 , which 20 is adapted to mesh with a bevel-pinion, l^6 , on a shaft, l^7 , by which power is communicated to the chain-wheels.

The shaft l^7 should be made laterally adjustable to accommodate the adjustment of the 25 guide k and the wheel l^5 . It is designed that each chain-wheel at the delivery end of the machine shall be driven in like manner.

There are steam pipes or coils i arranged below the tracks and connected with a steam- 30 generator for drying the cloth while it is being carried forward, or fans c' may be used for creating a current of air to effect the drying.

At the delivery end of the machine are the 35 drying-cylinders o , calendering-rolls S , and cloth-winding rollers w , as usual. Between the cylinders o and the ends of chains B is fitted the mechanism for straightening the figure of the cloth, as next described.

m m' are the first guide-rollers, sustained at 40 their ends in fixed brackets, the bottom of roller m being level with the tracks and roller m' elevated.

n n' are guide-rolls hung on side arms, n^2 , that are pivoted at the lower part of frame A. 45 A screw, p , fitted at each side of the machine and tapped into the arm n^2 , serves for adjustment of the arm and rollers n n' to and from rollers m m' . Roller n' is level, or nearly so, with roller m' , while roller n is lower and retains the cloth against the first cylinder o .

Between the guide-rollers m n' are numerous short rollers, r , placed as closely together as may be across the machine. These are carried in the forked outer ends of flexible or 55 jointed arms r' , sustained by a cross rod or bar, s' , that is held at its ends in brackets. Springs w' tend to raise the arms r' , and screws t' , tapped in a cross-bar, t , serve for holding the arms down as adjusted. These parts are shown 60 most clearly in Figs. 3 and 5. With this construction the rollers r are held always in one vertical plane transversely of the machine, while being capable of adjustment vertically, as illustrated in Fig. 4.

65 In operation the cloth passes from the chains

beneath roller m , then beneath and over roller m' , beneath rollers r , over roller n' , and beneath roller n to the steam-cylinders. The guide-rollers n n' act to bring the plaid or stripe on the cloth into position at right angles with 70 the side of the cloth, in case it has been thrown out by the tenting previously. This is accomplished by adjusting the arm n^2 to throw forward the ends of rollers n n' at the side of the machine, where the stripe or plaid needs 75 to be brought up. The rollers r act to straighten the plaids or stripes, if required. If the stripes are straight when they reach rollers r , such rollers should then be set on a horizontal line, either in or out of contact with the 80 cloth; but if the stripes or plaids are curved, or otherwise out of a straight line, the rollers, r will be set so that those at the ends bear on the cloth and the middle rollers free, or the reverse, as is required to straighten the figures. 85 The two sets of adjustable rollers n n' and r thus act, the first to bring the edges of the cloth up and the second to straighten the cloth between the edges, and the cloth is delivered to the calendering-rolls with the figure 90 correct, as designed.

A single flexible roll may be used in place of the rollers r . I do not limit myself in that respect, nor in the particular details of construction otherwise.

Having thus described my invention, I claim as new and desire to secure by Letters Patent—

95

1. The combination, with roll a , of the spreader, consisting essentially of bars b^2 , diagonally fluted in opposite directions from the middle, and pivoted end pieces, b' , provided with a ratchet-wheel, c^2 , and pawl d^2 , substantially as and for the purposes described.

2. The combination, with the wheels g , endless chains B , and tracks k , of the screw-shafts l , nuts l' , shaft l^7 and its gearings, and mechanism for driving the wheels g , substantially as shown and described.

3. The combination, with the cylinders o and rollers r , of the rollers n n' , winding-drum w , and the pulleys g^2 g^3 and belts g^3 g^3 , substantially as shown and described.

4. The combination of rollers r and mechanism for their vertical adjustment, with rollers m n' , substantially as and for the purposes specified.

5. The combination, with the guide-rollers n n' , the rollers r , and fixed guide-rollers m m' , of mechanism for adjusting the rollers n n' horizontally and rollers r vertically, as and for the purposes set forth.

6. The combination of arms r' , spring w' , adjusting-screws t' , rollers r , guide-rollers n n' and m m' , substantially as and for the purposes specified.

ALVIN WOODMAN.
